US00D917114S

(12) **United States Design Patent** (10) Patent No.: **US D917,114 S**
(45) Date of Patent: **** Apr. 20, 2021**

(54) **ANTI BARKING DEVICE**

(71) Applicant: **Yijun Tang**, Changsha (CN)

(72) Inventor: **Yijun Tang**, Changsha (CN)

(**) Term: **15 Years**

(21) Appl. No.: **29/749,128**

(22) Filed: **Sep. 3, 2020**

(51) LOC (13) Cl. **30-99**

(52) U.S. Cl.

USPC **D30/199**

(58) **Field of Classification Search**

USPC ..... D30/151–155, 144, 199, 160, 161, 112; 119/792–798, 850, 855–859, 863–865, 119/654, 905, 907, 815, 712, 802, 784, 119/769, 760, 776, 862, 908, 860, 119/719–721; 242/381.1–381.2, 385.4, 242/378.3, 376.1, 385.1, 916, 601, 570, 242/405, 404, 371, 223, 170, 388.1, 242/405.2, 377, 381.3, 381.6, 405.3, 242/388.6, 384.7, 382, 396.1, 404.1, 380; 362/108; 33/767, 769, 414; D12/400; D3/229, 230, 207, 208, 215; 40/1.5, 455, 40/640, 303; 206/63.3, 459.5, 702, 408, 206/457; D6/515; D8/358, 360, 347, D8/360.1, 359, 356, DIG. 1; D24/145, D24/167, 186, 146, 169; D10/57, 72, D10/106.1, 104.1, 104.2, 109.2, 70, 97, D10/98, 78, 65; D20/28; 224/666, 678; 16/445; 283/74, 70; D11/232, 200, 216, D11/1, 2, 86, 87, 201, 206–210, 212–215, D11/218; 24/163 K, 122.3, 323, 702, 24/600.4–600.7, 163 R, 169–171, 173, 24/177–179, 191, 194, 195, 197, 200, 24/303, 616, 635, 313, 615, 3, 6, 3 K, 24/599.2, 96, 221, 237, 311, 312, 314, 24/321, 338, 339, 309; 428/3, 4; 54/76, 54/1, 71; 63/29.1, 3; 191/12.2 R, 12.4; D13/154, 153, 137.4, 155, 103, 168;

CLAIM

The ornamental design for an anti barking device, as shown and described.

DESCRIPTION

FIG. 1 is a first perspective view of an anti barking device showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the anti barking device in which the design is embodied that form no part of the claimed design.

1 Claim, 8 Drawing Sheets
